UNITED STATES PATENT OFFICE.

HARRY J. McCUE, OF CLEVELAND, OHIO, ASSIGNOR TO THE H. J. McCUE COMPANY, A CORPORATION OF OHIO.

SODA FOUNTAIN.

Application filed March 25, 1921. Serial No. 455,379.

The present invention relating, as indicated, to soda fountains, is particularly directed to certain improvements in the construction of a soda fountain casing or cabinet; and to certain improvements in the arrangement of the apparatus and contents therein.

As heretofore constructed, soda fountain installations have been built in place or assembled at some point convenient to the place of use, and have been made of separate parts fastened together and guarded against leakage by various expedients, such as cementing or filling the joints. Furthermore, a plurality of drain connections have been used and the cooling effect of the drain water and brine has not been fully availed of. Likewise, the arrangement of the several compartments has not been made in the most effective manner to secure a maximum cooling effect throughout the apparatus.

Among the objects of my invention are the provision of a construction obviating the disadvantages incident to the practice above noted, simplifying the installation of a soda fountain apparatus at the place of use, and supplying a construction embodying many novel features for the most effective carrying out of its proper functions. To this end I provide an integral monolithic casing having insulated walls particularly arranged with respect to the several subdivisions of the casing, and provide for a circulation of the brine and drainage water so as to secure a maximum of cooling effect from the minimum amount of refrigerating mixture, and in place of a plurality of drainage connections provide a single drainage outlet with adequate facilities for keeping all the parts free of obstruction and in perfectly sanitary condition. To the accomplishment of the foregoing and related ends, the said invention, then, consists of the means hereinafter fully described and particularly pointed out in the claims.

The annexed drawing and the following description set forth in detail certain structure embodying the invention, such disclosed means constituting, however, but one of various mechanical forms in which the principle of the invention may be used.

In said annexed drawing:

Fig. 1 is a front elevation of my improved cabinet; Fig. 2 is a plan view of the same;

Fig. 3 is a section on the line 3—3 in Fig. 2; Fig. 4 is a section on the line 4—4, in Fig. 5; Fig. 5 is a section on the line 5—5, in Fig. 2; Fig. 6 is a section on the line 6—6, in Fig. 2; Fig. 7 is a longitudinal section on the line 7—7 in Fig. 3; Fig. 8 is a front elevation of the series of syrup containers; Fig. 9 is a bottom plan view of the same; and Fig. 10 is a section on the line 10—10 in Fig. 8, through one of such containers.

Referring now to Figs. 1 and 2, my improved fountain consists of a central casing or cabinet 1, mounted upon adjustable supports or legs 2 preferably telescopic screw-threaded sections as shown and provided on either side with the usual drain boards 3 and 4 which have the drain connections 6 and 7. Extending partially over the central cabinet 1 and the drain boards 3 and 4, is a counter or top 5 of the usual type. Mounted upon this counter at substantially the center are a series of draft arms 8, 9, 10, 11 and 12.

The centrally disposed casing or cabinet 1 is provided with a number of compartments which are shown in Figs. 3 and 7 and consist of the compartments 13 and 14, in which are usually carried the cans for ice cream and a central compartment 15 which is provided with a bottom portion of somewhat decreased area 16, in which there may be held bottles of various beverages, this compartment being provided with means for cooling it from the two adjacent compartments 13 and 14. Before describing the arrangement of the various parts of the apparatus, the construction of this central cabinet 1 or casing will be taken up.

As at present constructed, soda fountains or that portion of the fountain which excludes the central box-like cabinet are extremely expensive, not only to build but to assemble in a store. One of the principal objects of the invention, as has been stated, is the provision of a cabinet or casing for this purpose which may be constructed in a simple and inexpensive manner. I therefore construct my casing for this purpose of a single piece of concrete. The bottom walls and intermediate partitions may be formed integral with each other and in a single monolithic structure. Suitable reinforcing elements may be employed or an embedded steel frame may be used. The construction of this cabinet is best shown in

Figs. 3, 5, 6 and 7. In Fig. 3, the end walls 18 and 19, and the intermediate partition walls 20 and 21, as well as the front and rear walls 22 and 23, the lengthwise partition wall 24, and the bottom 25, are formed of concrete and are constructed integral with each other. The rear wall 23 and the central portion of the wall 24, I preferably make of greater height than the remaining 10 walls for a purpose to be later disclosed. Upon the upper surface of the bottom 25 there is mounted a layer 26 of cork on top of which is placed a layer 27 of some suitable sheet rock, such, for example, as slate, 15 gypsum, or the like, while on top of the sheet rock there is a relatively thick layer 28 of cork, which is, in turn, covered by a layer 29 of sheet metal, preferably of copper. The end walls, together with the front and back 20 walls, consist of a layer 30 of cork mounted against the inner face of these walls covered, in turn, by first a layer 31 of sheet rock and a second layer 32 of cork, and then a surface 25 layer 33 of metal. The transverse partition walls consist of a central layer 35 of concrete, upon one side of which is mounted a layer 36 of cork, and then a layer 37 of sheet metal, while on the other side of the concrete partition wall there is mounted 30 merely a layer 38 of sheet metal.

This concrete monolithic cabinet may be made at relatively small expense and when built up of the successive layers of the material described above, is an extremely good 35 insulator and requires no assembly after it is brought to the store where it is to be installed. It will be understood, of course, that any desired surface material, such as marble, or the like, may be mounted against 40 the outer surface of the concrete, and I have shown such a layer 40 in Figs. 5 and 6, together with drop boards 41 of the same material to cover the legs 2 from the front of the fountain. The two compartments 13 and 45 14 are designed to hold cans 45 which will contain ice cream, and broken ice usually with a mixture of coarse salt may be packed around these cans to maintain the cream in a frozen condition. Conduits 47 are provided approximately centrally of each of the 50 side walls of the compartments 13 and 14. The water draining from these two compartments is a very cold brine and is permitted to drain through the said conduits 47 into a 55 chamber 46, formed around the inner walls of the chamber 15, after the brine has reached the level of the said connecting conduits. This chamber has side arms and is of narrow width and approximately half the 60 height of the chamber 15. Its upper portion is provided with loose cover 58 and it has a connecting section 46' midway of the side arms which will serve to sub-divide the 65 chamber 15 into a front and back compartment. Within the front compartment bot-

tled beverages may be stored. The rear compartment of the chamber 15 is designed to hold the carbonated water tanks or soda coolers 55. The upper portion of the chamber 15 is partially closed by a series of 70 crushed fruit containers 56 seated about its side and back upper margins. The central portion of the chamber is then closed by a suitable cover 57. Sliding doors 48 are provided to cover suitable openings in the bottom of this surrounding chamber 46 for the purpose of draining all of the brine from the ice cream chambers when desired. The brine flowing around in the chamber 46 maintains the chamber at a temperature 80 which will enable it to cool carbonated water and bottle beverages and other contents of the chamber. The brine from the chamber 46 overflows through the conduit 50 in the partition wall 24 in the rear of this chamber 85 into a chamber 51 formed at the back, that is, on the counter side of the fountain. This chamber extends longitudinally the entire length of the casing and is provided at its base with a main water drain 61, which 90 receives all the water used in the various appliances upon the cabinet. This drain extends longitudinally the entire length of the casing and projects therefrom at one end. It is set at an angle to cause liquid received 95 therein to flow toward the projecting end thereof which, upon this extension 62, is provided on its under side with a connection with the main outlet drain 63 and on its upper side, diametrically opposite thereto, with an opening 64 having a plate 65 clamped thereover to permit of cleaning operations. The ends of the main water drain receive the respective lower ends of the drains 6 and 7 heretofore referred to. Below the lower end of the drain pipe 7, where it enters the more elevated end of the main water drain, is provided a clean-out plug 66. Above the main water drain is provided a partition 67 extending longitudinally 100 across the bottom of the longitudinal chamber 51 and separating it from the main water drain. Above the partition is placed a heavy cork insulation 68 covered with metallic sheeting 69. The upper surface of this 105 insulated partition is inclined at the same angle and in the same direction as the main water drain and near its lower end is provided with a brine overflow trap 71 having a drainage outlet 72 centrally thereof, which 110 is thus kept surrounded continually with cold brine. Above the more elevated end of the main brine drain upon the upper side of the partition 67 spaced therefrom and inclined in the reverse direction thereto, is provided a partition to serve as a brine conveyor 73 and provide for the circulation of the brine discharged through the conduit 50 into the longitudinal chamber 51. The lower 115 end of the brine conveyor is spaced from 120

125

130

the end wall of the casing so as to permit the brine flowing thereon to drop onto the inclined main brine drain before mentioned.

Within the upper portion of the longitudinal chamber 51 adjacent the respective ends thereof are positioned a plurality of syrup jars 52 illustrated in detail in Figs. 8, 9 and 10, provided with draft arm connections 81 upon their base portions and having clean-cut plugs 82 adjacent thereto. The syrup jars 52 are air tight and have a pressure connection 53 and cooperating cut-off valve 53', held in open position against the action of a closing spring 53", by an elongated valve stem 53", against which the front cover plate 54, of the jar bears when in seated position.

Centrally of the longitudinal chamber 51 are provided the various draft arm connections with the several syrup jars and soda coolers, as well as the drain pipes 83 from the drip plate 84 beneath the draft arms 85. Directly beneath the drip plate centrally of the casing, is provided a chipped ice basin 86 serving as an auxiliary cooler box comprising a rectangular receptacle within the central portion of said chamber and provided with an opening 87 and an appropriate closure 90 therefor in an upward extension of the partition wall 24. This upward extension 88 of the said partition wall is positioned centrally of the casing and its upper edge provides a support for the drip plate heretofore referred to. Immediately beneath the drip plate which has an inward inclination is provided a transverse partition 89 which closes the upper end of the longitudinal chamber 51 and supports a heavy cork layer upon its upper side.

From the preceding description, it will be obvious that an arrangement has been provided whereby the maximum cooling effect may be obtained from the cooling mixture utilized. Thus, the brine and salt packed about the ice cream cans provide a high degree of frigidity within the compartments 13 and 14, the upper portions of which are closed by the insulated covers 91. The brine resulting from the action of the freezing mixture is then conveyed into the compartment within the central chamber and there exerts a cooling effect upon the contents of said chamber. From the central chamber the brine then flows upon the special brine conveyors, the upper one carrying it to the extreme end of a longitudinal chamber and the lower one carrying it to the opposite end of said chamber. During its passage over the full extent of these conveyors, all the cold producing capacity of the brine will be very fully utilized prior to its discharge into the main water drain below the main brine conveyor. The positioning of the soda coolers, syrup jars and their connections, are most favorable for producing the

proper temperature of the liquid to be served. The arrangement of the crushed fruit containers serves the double purpose of closing a portion of the central receptacle, as well as favorably disposing these containers to receive the right amount of cooling temperature.

It will thus be noted that, through the use of my improved construction, the most effective disposition is made of the various appurtenances of a soda fountain installation, together with the most advantageous placing of the insulating means therefor, and that a unitary structure is thus provided which may be installed at the place of use with the least amount of labor and be maintained in sanitary and operative condition without difficulty.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. A soda fountain cabinet comprising a housing for fluid dispensing apparatus and a cold storage supply space open at its top, said cabinet being provided with interior partition walls, dividing the same into a plurality of chambers, and passage ways for cooling fluids connecting said chambers, said passage ways being spaced above the floor of such chambers to retain predetermined amounts of said cooling fluids in contact with the walls of said compartments, said partition walls and the other walls of said cabinet being formed integral with each other in one monolithic block.

2. A soda fountain casing comprising a monolithic structure having a plurality of integral partition walls providing compartments within said casing, and a heavy insulation supported upon said outer walls and fitted within floor sections of said compartments, one of said compartments having means adjacent its side walls for holding a cooling medium, said means communicating with adjacent compartments.

3. A soda fountain casing comprising a monolithic structure having a plurality of integral partition walls providing compartments within said casing, a heavy insulation supported upon said outer walls and fitted within floor sections of said compartments, one of said compartments having means adjacent its side walls for holding a cooling medium, said means communicating with adjacent compartments, and insulating means applied to the opposite face of each of said side walls.

4. A soda fountain casing comprising a monolithic structure having a plurality of

- integral vertical partition walls, one of said partitions providing a longitudinal service apparatus compartment, other of said partitions providing a transverse series of supply and refrigerating mixture compartments, and a plurality of brine circulating elements within said longitudinal compartment and applied to the walls of said transverse compartments.
- 10 5. In a soda fountain casing the combination of an integral monolithic series of compartments, a sheet rock insulation supported within the outer walls of said compartments and a copper lining over said insulating material.
6. In a soda fountain casing the combination of an integral monolithic series of compartments, a sheet rock insulation supported within the outer walls of said compartments, layers of cork upon each side of 20 said sheet rock insulation, and a copper lining over said insulating material.

Signed by me, this 17th day of March, 1921.

HARRY J. McCUE.
